(57) **CLAIM**

The ornamental design for a valve positioner for the distribution of fluid and gas, as shown and described.

DESCRIPTION

FIG. 1 is a front elevational view of a valve positioner for the distribution of fluid and gas showing our new design; FIG. 2 is a back elevational view thereof; FIG. 3 is a top plan view thereof; FIG. 4 is a bottom plan view thereof; FIG. 5 is a right side elevational view thereof; FIG. 6 is a left side elevational view thereof; and, FIG. 7 is a top, front, right perspective view thereof.
